FLUSH TANK VALVE

Rolland P. Wiley, Kansas City, Mo.

Application February 7, 1944, Serial No. 521,368

2 Claims. (Cl. 137—104)

1

This invention relates to flush tank valves of the character wherein is employed float ball actuated structure for controlling the flow of water into the tank, and the primary object is the provision of an improved valve of such character.

One of the important aims of this invention is the provision of a flush tank valve having as a part thereof, a uniquely designed and disposed valve seat and head, both of which are confined within a hood, carried by the float ball actuated structure and shrouding the upper end of the water supply pipe.

A still further object of this invention is to provide a flush tank valve having means for directing the flow of water from the supply pipe through downward paths of travel to prevent objectionable spraying and possible escape of the water from the tank.

Further objects of the invention include the manner in which the above mentioned hood and associated parts may be adjustably maintained above the water level; the employment of parts within the flush valve that eliminate the necessity for using conventional flush tubes; and the provision of valve parts having readily accessible and renewable valve seats and heads that may be adjusted or replaced with a minimum amount of time and effort.

Other objects of the invention, setting forth the manner of forming the elements of the improved flush tank valve and the materials from which the parts are preferably created, will appear during the course of the following specification, referring to the accompanying drawing, wherein:

Fig. 1 is a side elevational view of a flush tank valve removed from the operative position in the tank and having parts broken away for clearness, which valve embodies the present invention.

Fig. 2 is a fragmentary vertical central sectional view through the upper portion of the flush tank valve; and

Fig. 3 is a cross sectional view taken on line III—III of Fig. 1.

Present day shortages of critical materials, such as copper and brass, and the desirability of employing plastics in the construction of elements such as form a part of the flush tank valve illustrated, dictates that certain of the following identified elements be made of moldable, corrosion resisting substance and less critical metals.

The valve illustrated and about to be described is desirable in that it is particularly adapted to the use of the materials just mentioned.

2

In the drawing the flush tank per se is not illustrated, but the fittings broadly designated by the numeral 4 by means of which the valve may be mounted, are shown on normally vertical pipe 6, the end portions whereof are screw-threaded as at 8 and 10 respectively.

Fittings 4 are adjustably connected to pipe 6 by threads 8 and support 12 is likewise carried at the upper end of pipe 6 through the medium of threads 10. Set screw 14 is supplied to maintain support 12 in the adjusted position.

Support 12 is substantially U-shaped and its legs 16 and 18 respectively are bifurcated at their upper free ends to form yokes 20 and 22 respectively. Arm 24 has one end thereof pivotally supported by yoke 22 as at 26 and extends transversely across support 12 to yoke 20 to a pivotal connection 28 with one end of link 30. This short link has its other end pivotally joined as at 32 to arm 34 fulcrumed on yoke 20 through the medium of a transverse pin 36. The end of arm 34 opposite to that connected to link 30 carries float rod 38 upon which is mounted the conventional float ball not here shown.

The upper end of pipe 6 carries a notched head 40 having a form shown in Fig. 2, and generally frusto-conical in shape. This head is in screw-threaded engagement with pipe 6 and has a bore 42 in alignment with pipe 6 to permit free flow of water.

A series of guide lugs 44 extending radially from head 40, are created through the formation of a number of longitudinal notches 46. This head 40 is disposed within hood 48, preferably formed of plastic and having the cross sectional contour illustrated in Fig. 2. A gasket 50 carried within hood 48, lies against the innermost or bottom face thereof to rest upon the upper end of head 40 when the valve is closed. The inside diameter of socket 52 is substantially the same as the outside diameter of head 40 where lugs and notches 44 and 46 respectively, are provided.

The length of that portion of bore 52, which houses the larger section of head 40, is greater than the length of lugs or notches 44 and 46 respectively, and therefore, as longitudinal reciprocation of hood 48 occurs, the outer faces of guide lugs 44 will slidingly engage the inner face of hood 48 forming bore 52 to prevent lateral displacement. This guidance may take place as water is passing from the bore 42 of head 40 because the notches allow the water to escape from within the hood.

A laterally projecting duct 54 in hood 48 joins bore 52 above the enlarged portion of head 40

and is in connection with tube 56 which extends to the conventional overflow pipe of the flush tank assembly, as is well-known in the art.

Tube 56 is in screw-threaded connection with hood 48 and may be renewed if necessary. Gasket 50 is formed of some pliable material and effectively seals the upper end of bore 42 when the valve mechanism is closed.

A loop 58 mounted upon the top of hood 48, has a stem 60 in screw-threaded engagement with a socket provided in hood 48. Loop 58 receives arm 24 and arm 34 rests upon the top of loop 58, all as clearly illustrated in Figs. 1 and 2. Thus, as float rod 38 is raised from the position illustrated in Fig. 1, arm 24 moves in the direction of the arrow shown in Fig. 1 to drop gasket 50 to its seated position upon the upper end of head 40. Water will thereupon cease to flow from pipe 6 through head 40 into hood 48, from where it had been flowing therefrom in a downward direction through notches 46. No radial spraying or other objectionable flow of water can occur.

The operation of the flush tank valve is clear from the foregoing specification, and it will be apparent that as water passes downwardly from within hood 48, that portion of the interior of the hood above the larger part of head 40, will be maintained filled with water under a slight pressure, sufficient to supply duct 54 and tube 56.

All of the float valve actuated structure is carried by support 12 and any mal-adjustment between gasket 50 and the end of head 40 may be overcome by moving support 12 along pipe 6 and installation is facilitated through the employment of the parts in their aforesaid relation. Renewal of gasket 50 is an exceedingly easy matter for the hood 48 may be removed simply by manipulating pivot pins 26 and 36.

The water line in the tank is always below the bottom of hood 48 for the purpose of maintaining a permanent vacuum breaker. This level is controlled by the float ball and the angularity of rod 38.

Critical materials are reduced to a minimum in the valve assembly. Pipe 6 is a conventional galvanized iron conduit; support 12 and hood 48 are molded from plastic material; and gasket 50 is of synthetic rubber or the like. Only parts 40, 58, 24, 30 and 34 are made of brass, resulting in the use of but four ounces of this critical material.

From the above it will be clear that not only is the flush tank valve unique and novel in its physical characteristics, but that the substances from which it is made are readily available and capable of meeting the demands of the use to which they are put.

Having thus described the invention, what is

claimed as new and desired to be secured by Letters Patent is:

1. In a flush tank valve, a pipe having means for connecting one end thereof with a source of water supply and having its other end open; a support in screw-threaded engagement with the pipe adjacent to its upper end whereby the support may be shifted axially of the pipe; a hood shrouding the said open end of the pipe; a gasket on the innermost wall of the hood; a head having a bore therethrough on the open end of the pipe, within the hood for cooperating with the gasket to control the flow of water from the pipe; said head being smaller in outside diameter than the inside diameter of the hood; laterally extending guide lugs on the head in sliding engagement with the inner face of the hood to prevent lateral displacement thereof; and float ball actuated structure on the support and having connection to the hood for shifting the same to and from a position where the gasket is closing the bore through said head.

2. In a flush tank valve, a pipe having means for connecting one end thereof at its lower end with a source of water supply and having its other end open; a support in screw-threaded engagement with the pipe at a point spaced downwardly from the upper end thereof, whereby the support may be shifted axially of the pipe by turning the same about the axis of the pipe; an inverted cup-shaped hood shrouding the open end of the pipe and telescoping the open-end portion of the pipe; a gasket on the innermost wall of the hood; a substantially frusto-conical head, having a bore therethrough, on the open end of the pipe within the hood and cooperating with the gasket to control the flow of water from the pipe; longitudinal notches in the base of the said hood; and float-ball actuated structure on the support for shifting the hood toward and from the inner end of the head, the outside diameter of the frusto-conical head at its base being substantially the same as the inside diameter of the head, said head being in screw-threaded engagement with the pipe.
